UNITED STATES PATENT OFFICE.

OSCAR KATZENBERGER, OF CHICAGO, ILLINOIS.

JAMB SPRING-HINGE.

1,242,700.

Specification of Letters Patent.

Patented Oct. 9, 1917.

Application filed December 26, 1916. Serial No. 138,798.

To all whom it may concern:

Be it known that I, OSCAR KATZENBERGER, a citizen of the United States, and a resident of Chicago, in the county of Cook and State 5 of Illinois, have invented a new and Improved Jamb Spring-Hinge, of which the following is a full, clear, and exact description.

This invention relates to spring hinges 10 and has for an object the provision of an improved construction of jamb hinge that may be used on a jamb of any width without the use of a hanging strip or without mortising the jamb.

Another object in view is to provide a 15 jamb hinge designed to be countersunk only in the door.

A still further object in view is to provide a jamb hinge with a pair of drums and 20 a connecting plate formed to resist the strain in such manner that the strain will be distributed throughout the plate.

In the accompanying drawing:—

Figure 1 is a sectional view through Fig. 25 3 on line 1—1.

Fig. 2 is a face view of the door jamb with the door and hinge moved to one side.

Fig. 3 is a transverse horizontal section through Fig. 1 on line 3—3.

Fig. 4 is a sectional view through Fig. 3 on line 4—4.

Fig. 5 is a sectional view through Fig. 2 on line 5—5.

Fig. 6 is a front view of the drums and 35 connecting plate, together with a reinforcing member associated therewith.

Referring to the accompanying drawings by numerals, 1 indicates a door jamb to which the door 2 is pivotally connected by 40 one or more hinges. In arranging the hinge in position it will be noted that the jamb 1 is not in any way countersunk or cut as indicated by Fig. 4 while the door is cut to an appreciable extent for accommodating 45 certain parts of the hinge. As shown in Figs. 3 and 6 the hinge is provided with a body 3 which is formed from a plate bent so as to produce the barrels 4 and 5 and overlapping leaves 6 and 7. The leaves 7 50 are formed so that their edges will be at an angle, as shown in Fig. 6, said angle being diagonal from top to bottom of the body 3 whereby a plurality of fastening rivets 8 may be used for forming a rigid body and 55 for causing the strain to be distributed throughout the body on both of the leaves

instead of centrally of the body on one leaf, which would be the case if the meeting edges of the parts of leaf 7 were in the center. In the drawing a double-acting 60 hinge has been shown for the purpose of illustration, but it is evident that the construction would apply to a single acting hinge without departing from the spirit of 65 the invention.

In order to provide a proper reinforcing and stiffening member an extra plate 9 is provided, said plate having extending edges 10 and 11 bracing against the barrels 4 and 5, and turned-over ends 12 and 13, as shown 70 particularly in Fig. 4. End 13 is shown straight in Fig. 6 merely for the purpose of illustration. A leaf 14 is provided and formed with a section which receives the retaining screws 15, the turned-up ends 17 75 and 18 fitting the top and bottom of the notched-out section 19 in door 2. The leaf 14 is provided with end members 16 and 20 and also with a bracing wall 21 against which the pin 22 rests when the hinge is in 80 operation. A pintle 23 extends through the ends 16 and 20 and also through the barrel 4 so as to hold the parts in proper position. A spring 24 is arranged in barrel 4 with one end connected to the end 16 in any suitable manner and the opposite end to a winding disk 25, which winding disk is formed with a plurality of apertures 26 for accommodating the lug or pin 22, whereby 85 the spring may be wound to any desired extent.

Barrel 5 is provided with a leaf 27, which leaf is fitted on to the barrel 5 in a similar manner to the way leaf 14 is fitted on to barrel 4, the leaf being associated with a 90 spring pintle and other parts similar to barrel 5 and will therefore need no additional description, leaf 27 being connected to the jamb 1 while leaf 14 is connected to the door 2. It will be noted that in forming the body 3 and the barrels 4 and 5, the barrels are arranged on one side, or, rather, on one face of the body 3, whereby the leaf 27 may properly fit flatwise against the door frame or jamb 1. In fact, the hinge could be placed against a wall and properly secured in position and support a door designed to swing in both directions or one direction, as all the swinging movement is done from the center of the respective barrels. In producing this result the leaf 14 100 is formed of the turned-up members 17 and 105 110

18 whereby a socket is provided which receives the central part or body 6 and also part of the leaf 27. It will be noted that the central leaf section formed of barrels 4 and 5 and the body 6 is constructed of one piece of material and the body 6 is reinforced by the rivets 8 and plate 9.

In arranging jamb hinges in place on the jamb it has been customary to place in position what is known as a hanging strip, said strip being mortised into the jamb and, consequently, being placed accurately. By arranging the parts as shown in the drawing and as described above, no hanging strip is necessary, and, consequently, no mortising of the jamb as all of the mortising is done in the door. This result is attained, as shown in the drawing, by forming the barrels on the edges of the body and one face thereof, which leaves sufficient space between the barrels and the jamb to avoid frictional engagement whether the hinge is a single or double acting jamb hinge. One of the objects in producing a hinge which will not need a hanging strip mortised into the jamb is that said strip must be accurately positioned or the door will not hang properly, while by providing a hinge which is mortised into the door only and secured to the jamb at any point the door may be hung accurately without any appreciable trouble.

What I claim is:

1. A jamb hinge comprising a pair of barrels and a body formed of one piece bent so as to produce the two barrels on the edges of the body and on one face thereof and to produce a body having a solid section and a divided section, said divided section being arranged with a division line diagonally across the body whereby vertical strain will be distributed to all parts of the body, means for rigidly connecting said sections together, a pair of leaves, means for resiliently connecting one of said leaves with one of said

barrels, and means for resiliently connecting the other of said leaves with the other barrel. 45

2. In a double swinging or three-leaf hinge, a central leaf section formed from a single sheet of metal bent for producing a pair of barrels at each edge, a central solid body portion and a pair of body end members arranged with their meeting edges at a diagonal whereby the vertical strain will be taken up by all of the body portions, and means for clamping all of said body portions rigidly together. 50 55

3. In a hinge of the character described, a central leaf section formed with a pair of barrels, a body portion formed from a plurality of plate portions merging into said barrels, one of the plate portions having diagonal meeting edges, a reinforcing plate having edges for bracing said barrels and overlapping ends for clamping the upper and lower edges of the body portion, said overlapping ends covering part of said diagonal meeting edges and a plurality of rivets for clamping said plate and said plate portions together. 60 65 70

4. In a hinge of the character described, a leaf provided with a bottom formed with screw receiving openings and end flanges whereby a socket structure is produced designed to fit into the mortise in a door, a central leaf section having a barrel on each edge thereof, said barrels being on the same face of their connecting section and spaced outwardly from the jamb when in use, one of said barrels being pivotally mounted on said first mentioned leaf and the second mentioned leaf being pivotally mounted on the other barrel, said last mentioned leaf and the connecting section between said barrels fitting within the turned-up ends of the first mentioned leaf. 75 80 85

OSCAR KATZENBERGER.
